Patented Nov. 2, 1920.

UNITED STATES PATENT OFFICE.

EDGAR M. MCLEAN AND CHARLES B. YODER, OF ST. LOUIS, MISSOURI, ASSIGNEES TO
EVENS & HOWARD FIRE BRICK COMPANY, OF ST. LOUIS, MISSOURI, A CORPORA-
TION OF MISSOURI.

LOCOMOTIVE-FIRE-BOX ARCH.

1,357,575.

Specification of Letters Patent.

Patented Nov. 2, 1920.

Application filed September 9, 1916. Serial No. 119,242.

To all whom it may concern:

Be it known that we, EDGAR M. MCLEAN and CHARLES B. YODER, citizens of the United States, residing at city of St. Louis, State of Missouri, have invented a certain new and useful Improvement in Locomotive-Fire-Box Arches, of which the following is a full, clear, and exact description, such as will enable others skilled in the art 5 to which it appertains to make and use the same, reference being had to the accompanying drawings, forming part of this specification.

Our invention relates generally to improvements in locomotive furnaces and more particularly to the arches which are usually located in the front portions of the locomotive fire boxes. These arches are usually made up of specially formed bricks or 15 blocks of refractory material, said arches being for the purpose of directing the heat and products of combustion in their passage from the bed of fuel on the grates to the boiler flues.

The principal objects of our invention are to construct the arch forming bricks or blocks so that they may be readily assembled or taken apart; to form the end portions of the bricks or blocks so that they will 20 interlock when brought into proper assembled relation, thereby minimizing the tendency of the bricks or blocks to separate, particularly to such an extent as to permit one or more blocks to drop from the arch; to form the lower portions of the arch forming members so that they will rest loosely upon the arch supporting tubes, thereby permitting the latter and the arch forming members to have free independent movement, the latter being the result of expansion and contraction due to variations in temperature; to construct the arch forming members so that they cannot drop into position between the arch supporting tubes and 25 exert wedging action thereupon; to provide an arch construction which is made up of a minimum number of differently shaped bricks or blocks; and to form the bricks or blocks so that they may be interchangeably used in the construction of the arch, thereby materially minimizing the initial cost of 30 installation and repair of the arches.

With the foregoing and other objects in view, our invention consists in certain novel features of construction and arrangements 55 of parts hereinafter more fully described, claimed and illustrated in the accompanying drawings, in which,

Figure 1 is a perspective view of one of the arch forming blocks contemplated by 60 our invention.

Fig. 2 is a plan view of a portion of a locomotive boiler furnace showing an arch 65 of our improved construction positioned therein.

Fig. 3 is a vertical section taken through the center of a locomotive fire box and showing the same equipped with a type of the arch illustrated in Fig. 2.

Fig. 4 is an enlarged cross section taken 70 approximately on line 11—11 of Fig. 2.

Fig. 5 is an end elevational view of the spacing block.

Fig. 6 is a plan view of the universal spacing block constructed in accordance with our 75 invention.

Referring by numerals to the accompanying drawings, 10 designates the flue sheet which serves as the front wall of the fire box; 11 the rear end sheet; 12 the crown 80 sheet and 13 the side sheets.

The type of arch illustrated in Figs. 1 to 4, inclusive, is particularly designed for use in connection with locomotive fire boxes having a series of arch tubes 14^a and in the 85 form of fire box illustrated, there is a pair of these tubes arranged between the longitudinal center of the fire box and each of the side sheets thereof. The central portion of the arch is made up of a series of substantially rectangular blocks or bricks 24, the ends of which are provided with square lugs 25. The lower portions of these lugs are cut away as designated by 27 so that said lugs are substantially thinner than the 90 body portion of the block and when the blocks are properly positioned for use the flat under faces of said lugs rest directly on top of the central pair of tubes 14^a. Positioned on top of the pairs of tubes 14^a at 95 the ends of the blocks 24 are substantially rectangular blocks 28, each provided on one side with a recess 29 and on the opposite side with a lug or extension 30. The re-

cesses 29 are substantially rectangular shape when viewed in plan in order to receive the lugs or extensions 25 of the central row of blocks 24. The lower corners of both sides of 5 the blocks 28 are cut away as designated at 31 thereby making the side portions of said blocks substantially thinner than the body portions and the flat under faces of these comparatively thin side portions bear directly 10 on top of the pairs of tubes 14^a. The blocks 32 forming the sides of the arch occupy inclined positions between the outer tubes 14^a and the side sheets of the fire box and each block of the side row is provided at 15 its inner end with a recess 33 which receives the corresponding extension on the adjacent block 28. These recesses 33 are square shape. The lower inner corner of each block 32 is cut away as designated at 34 so as to form a 20 portion which is comparatively thinner than the main body portion of the block and the flat under face of this comparatively thin portion bears directly on top of the corresponding arch tube 14^a. The outer ends 25 of the blocks 32 are inclined or beveled with respect to the planes occupied by the top and bottom faces of said blocks so that when the blocks are properly positioned for use, said inclined or beveled faces occupy 30 substantially vertical positions and bear directly against the inner faces of the side sheets of the fire box. It is also preferable, though not essential, that the outer corners of the blocks 32 be cut away as designated by 35, Fig. 2, so that only the central portions of the blocks 32 bear against the side sheets of the fire box. Such construction permits the blocks forming the side rows of the arch to rock slightly through a substantially 40 horizontal plane, such rocking movement resulting from expansion and contraction due to variations in temperature and also to vibration of the fire box while the locomotive is in service. Owing to the manner 45 in which the various blocks entering into the construction of the arch are formed, the central row of blocks 24 can be turned end for end and the blocks 28 and 32 forming the side rows can be utilized to complete 50 either side of the arch and by virtue of such construction the initial cost of the arch is materially reduced, likewise the repair of the arch, for, by thus making said blocks reversible and interchangeable, it is not necessary for locomotive builders or 55 users to carry in stock a comparatively large number of blocks of different shapes and sizes.

The spacing block 36 utilized between the 60 lower forward end of the arch and the flue sheet is illustrated in Figs. 5 and 6, said block being substantially rectangular in form and having length, width, and thickness of definite dimensions, for instance it 65 has been found desirable and advantageous

to provide a block having a length of six inches, a width of four inches, and a height of three inches. Formed in the under side of this block is a centrally arranged longitudinally disposed groove 37 and a centrally arranged transversely disposed groove 38. These grooves are of such size as to receive the upper portions of the arch tubes 14^a. Formed in one side of the block is a centrally arranged vertically disposed groove 39 which, when the block is turned into a vertical position, receives the upper portion of one of the arch tubes. One of the upper corners of the block is cut away to form an angular or beveled face 40 and the upper corner of the side opposite the side in which the groove 39 is formed, is cut away to form a beveled or angular face 41. When this block 36 is positioned lengthwise upon a tube with the latter positioned in 85 groove 37, the beveled face 40 bears against the flue sheet 10 as illustrated in Figs. 1 and 2 and when said block is transversely disposed on one of the tubes with the latter occupying groove 38, bevel face 41 bears 90 against the flue sheet. When the block is vertically disposed and with one of the tubes positioned in groove 39, the corner or edge between bevel face and the top face of the body of the block bears against the flue sheet. 95

By our improved construction of spacing blocks, it is possible by varying the relative positions of the blocks to form spaces of varying widths between the lower front edge of the arch and the flue sheet. For 100 instance, when the blocks 36 are disposed in substantially upright positions and with the tubes resting in the notches 39, the front lower edge of the arch will be spaced away from the flue sheet a distance slightly 105 greater than three inches and by turning the same block so that it occupies a position lengthwise upon the arch supporting tube, the lower front end of said arch will be spaced apart from the flue sheet a distance of six inches. Further, when the block is turned transversely so that the flue rests in the groove 38 the lower front edge of the arch will be spaced apart from the flue sheet a distance of four inches. 110

It is the present practice to provide two or more sizes of spacing blocks and said practice requires that the users of locomotives carry in stock a comparatively large number of blocks of different sizes 115 in order to meet certain requirements, but by our improved construction it is only necessary to carry in stock one size of spacing block. By utilizing blocks of our improved construction arches for locomotive 120 fire boxes can be easily and cheaply provided and kept in repair. The blocks are supported by the arch tubes in such a manner that said tubes and blocks can move independently of each other and as said 125 130

blocks bear only upon the highest points of the tubes, practically the entire area of the tube surface is exposed to the heat from the furnace fire. The ends of the blocks 5 entering into the construction of the arch are interlocked in such a manner as to reduce to a minimum the tendency of the blocks in the various rows to get out of alignment and as all of the blocks in each 10 longitudinal row are of the same size and construction said blocks can be interchangeably used on either side of the arch, thus greatly facilitating the installation and maintenance of the arches and materially 15 reducing the cost thereof.

It will be readily understood that minor changes in the size, form and construction of the various parts of our improved locomotive fire box arch can be made and substituted for those herein shown and described, without departing from the spirit 20

of our invention, the scope of which is set forth in the appended claim.

We claim:

In combination with a locomotive fire 25 box provided with front and rear water legs, an arch composed of a series of inter-engaging blocks, the ends of the adjacent blocks being cut away so as to form substantially semi-circular grooves when said 30 blocks are assembled, and a series of water tubes traversing the grooves, the diameter of the water tubes being substantially smaller than the width of the grooves.

In testimony whereof we hereunto affix 35 signatures in the presence of two witnesses, this 2nd day of Sept., 1916.

EDGAR M. McLEAN.
CHARLES B. YODER.
